NOZZLE FOR VACUUM CLEANERS

Clarence A. Brock, Detroit, Mich., assignor to
 Rexair, Inc., Detroit, Mich., a corporation of
 Delaware

Application February 21, 1941, Serial No. 379,920

6 Claims. (Cl. 15—157)

This invention relates to nozzles for vacuum cleaners, the principal object being the provision of a nozzle for a vacuum cleaner that is simple in construction, efficient in operation and relatively economical to produce.

Objects of the invention include the provision of a vacuum cleaner nozzle having an improved means for dislodging threads and the like from the surface of a carpet, rug or the like; the provision of a device of the type described having an improved comb structure associated therewith for the purpose of aiding the picking up of threads, lint and the like from the surface of a carpet or rug; the provision of a vacuum cleaner nozzle having a comb movably associated therewith and so constructed and related to the vacuum cleaner nozzle structure as to insure withdrawal of threads or the like encountered by the comb into the nozzle; the provision of a comb structure for a vacuum cleaner nozzle that is normally operative but may be rendered inoperative when desired; the provision of a comb structure for a vacuum cleaner nozzle or the like including a pivotally mounted comb structure adapted when in one position to substantially contact the surface of a rug or carpet being cleaned and when in another position to be substantially out of obstructing relation with respect to the throat of the vacuum cleaner nozzle; the provision of a vacuum cleaner nozzle having a comb element movably mounted therein together with operating means therefor adapted to engage the surface of a carpet or rug being cleaned and adapted to actuate the comb between two opposite limits of its movable position each time the direction of movement of the nozzle on the surface being cleaned is reversed the movement of the comb serving to pick up threads, lint or the like which it has gathered from the surface being cleaned and carrying such threads or the like out of contact with the surface being cleaned and up into the nozzle where it is easily handled by the flow of air therethrough; the provision of a vacuum cleaner nozzle having a movable comb associated therewith so constructed and arranged as to be operated between its opposite limits of movement during a normal cleaning operation and so constructed and arranged when in one of its positions it partially obstructs the flow of air into the nozzle thereby to provide a high velocity stream of air to clean the comb of any threads or other foreign material which it may have picked up from the carpet; the provision of a vacuum cleaner nozzle having a comb associated therewith for substantial contact with the surface being cleaned and so constructed and arranged as to be shifted from one limit of its movable position to the other each time the direction of movement of the nozzle on the surface being cleaned is reversed; and the provision of a novel

comb construction for a vacuum cleaner nozzle and means for mounting the same.

Other objects of the invention include the provision of a vacuum cleaner nozzle including a laterally elongated body portion and a hinge member pivotally secured thereto and interiorly communicated with the interior of the body portion, together with an improved form of packing between the body portion and the hinge member serving to effectively seal the joints between them against the leakage of air; the provision of a vacuum cleaner nozzle of the type described in which the hinge member is provided with a plurality of grooves in its lower surface which may be positioned, by suitable positioning of the hinge member to permit a plurality of relatively small streams of air at high velocity to pass therethrough, and when the wand and, therefore, the hinge member is in another of their pivotal positions such channels or grooves are rendered inoperative for the purpose described.

Further objects of the invention include the provision of a vacuum cleaner nozzle including an elongated metallic body portion and a substantially surrounding bumper or padding element, the two being so constructed and arranged as to cooperate with one another to provide a streamlined housing; the provision of a vacuum cleaner nozzle including a transversely elongated metallic body portion providing angularly disposed walls, together with a bumper element removably received thereby and cooperating therewith to provide a nozzle structure of improved operation and appearance.

35 The above being among the objects of the present invention the same consists in certain novel features of construction and combinations of parts to be hereinafter described with reference to the accompanying drawings, and then claimed, having the above and other objects in view.

40 In the accompanying drawings which illustrate suitable embodiments of the present invention and in which like numerals refer to like parts throughout the several different views,

45 Fig. 1 is a side elevational view of a vacuum cleaner and an associated wand terminating in one form of a nozzle constructed in accordance with the present invention;

Fig. 2 is an enlarged front elevational view of 50 the vacuum cleaner nozzle shown in Fig. 1;

Fig. 3 is a side elevational view of the nozzle shown in Fig. 2;

Fig. 4 is a top plan view of the nozzle shown in Figs. 2 and 3;

55 Fig. 5 is an enlarged transverse sectional view taken on the line 5—5 of Fig. 2 and illustrating the comb element in its normal position of operation during forward movement of the nozzle;

Fig. 6 is a view similar to Fig. 5 but illustrating the comb element in an intermediate position of movement;

Fig. 7 is a view similar to Figs. 5 and 6 but illustrating the comb element at the opposite limit of its movement from that shown in Fig. 5, the same being its normal position during rearward movement of the nozzle;

Fig. 8 is a slightly enlarged fragmentary sectional view taken on the line 8-8 of Fig. 6 and illustrating the construction of the operative edge of the comb element in greater detail;

Fig. 9 is a partially broken top plan view of a vacuum cleaner nozzle incorporating a comb similar to that shown in the previous views but as a part of an improved structure;

Fig. 10 is a rear elevational view of the nozzle shown in Fig. 9;

Fig. 11 is a side elevational view of the nozzle shown in Figs. 9 and 10;

Fig. 12 is an enlarged vertical sectional view through the nozzle shown in Figs. 9, 10 and 11, taken centrally of the hinge member and as on the line 12-12 of Fig. 10;

Fig. 13 is an enlarged vertical sectional view taken on the line 13-13 of Fig. 10 and illustrating the method of supporting the comb element therein;

Fig. 14 is an enlarged fragmentary, enlarged bottom plan view showing the undersurface of one end of the nozzle shown in Fig. 10 and taken looking in the direction of the arrows 14-14 of Fig. 10, illustrating further details of the comb construction with greater clarity;

Fig. 15 is an enlarged, fragmentary horizontal sectional view taken on the line 15-15 of Fig. 11 and particularly illustrating the seal between the sides of the hinge member and the main body portion of the nozzle;

Fig. 16 is an enlarged vertical sectional view taken on the line 16-16 of Fig. 10 and illustrating a means for rendering the comb element inoperative;

Fig. 17 is an enlarged perspective view of the hinge member of the nozzle shown in Fig. 10;

Fig. 18 is a partially broken, partially sectioned rear elevational view of a still further modified form of nozzle construction; and,

Figs. 19 and 20 are enlarged vertical sectional views taken respectively on the lines 19-19 and 20-20 of Fig. 18.

There are two main types of vacuum cleaners on the market today. One of these is that type in which the vacuum producing mechanism and the nozzle therefor are built and operated as a unit and are usually contained within a single casing. The other type is that in which the nozzle is made relatively small and provided with a so-called wand or tubular handle for manipulating the same and is connected by a flexible hose to a suitable source of vacuum or vacuum producing apparatus. In the first of the above described types and because of the source of power for the vacuum producing mechanism, usually an electric motor, is closely associated with the nozzle, it is possible to incorporate a rotating brush means in the nozzle driven from the vacuum producing means for the purpose of facilitating the picking of threads, lint and other material which adheres to the surface of a carpet, rug or the like with considerable tenacity, this without appreciably increasing the bulk of the device which in any event is necessarily somewhat bulky. The advantage of the second type of structure is that a relatively small and light nozzle may be employed which is easily handled, is not tiring to operate, and may be projected into spaces and areas incapable of being reached with vacuum

cleaners of the first described type. It is not possible to incorporate a rotating brush in the nozzles of the second type of vacuum cleaners as above described without destroying the very advantages of this type of vacuum cleaner as compared to the first type, that is to do so would necessarily so increase its size, bulk and weight of the nozzle as to destroy its otherwise inherent advantages.

10 Much time and money has been spent particularly by manufacturers of the second type of vacuum cleaner above described to develop a novel structure which would with certainty pick up threads, lint and the like which adhered tenaciously to the surface of the carpet or rug without destroying the inherent advantages of this type of nozzle, but as far as I am aware up to the present time there has been no successful commercial development in this respect of any importance. I am aware that such prior attempts have involved the use of a so-called comb, an element having a serrated edge arranged in conjunction with the nozzle and positioned in operative relation with respect to the surface of a carpet or rug being cleaned so as to mechanically engage and release threads, lint or the like adhering to the surface of the carpet during movement of the nozzle thereover, but these have not been commercially practical for a number of different reasons. One of these reasons is that although such combs have been able to loosen threads or the like from the surface of the carpet, such threads simply form windrows in front of the comb which does not pick them up and mechanically transfer them to the interior of the nozzle, the result being that on reverse movement of the nozzle, the nozzle simply slides over such windrow and does not pick all of it up.

15 A vacuum cleaner nozzle for ordinary cleaning purposes must have an opening exposed to the surface being cleaned of material area through which the flow of air consequently is not of extremely high velocity. I have found that in order to remove threads, lint, or the like which have the tendency of adhering strongly to the surface of a carpet or a rug, not only must it be loosened from the carpet and be mechanically transferred to the interior of the nozzle, but it must be subjected to the effects of a stream of air of relatively high 20 velocity in order to insure its being completely removed from the surface of the carpet and from the comb and discharged into the machine.

25 The present invention provides a construction in which the opening in the nozzle for a vacuum cleaner is of sufficiently great area for ordinary cleaning purposes, is provided with a comb element for dislodging threads, lint or the like from the surface of a carpet or rug, and during operation of the nozzle the thread, lint, or the like is removed from the surface of the carpet or rug and mechanically transferred to the interior of the nozzle where it is subjected to the effects of an air stream under high velocity to insure its being withdrawn into the nozzle and discharged 30 into the usual dust receptacle. This is accomplished by providing a comb element within the nozzle and mounting it so that preferably during normal forward movement of the nozzle over the surface being cleaned the comb element is positioned in operative relation with respect to the surface being cleaned whereby to engage, dislodge and gather pieces of thread, lint, or the like adhering to the surface of the carpet. While the comb element in such position may have the 35 effect of slightly constricting the area of the

nozzle opening, this restriction is not material and the nozzle may be readily designed so that no restriction in effect actually exists. When the forward direction of movement of the nozzle is reversed the comb element is moved to mechanically pick up the threads so gathered and transfer them to the interior of the nozzle, and in being so moved the comb restricts the flow of air through the nozzle, thus increasing its velocity. In positioning the threads, lint or other material which the comb has picked up in the path of flow of this high velocity air, it insures that such threads or the like will be withdrawn into the nozzle in the manner desired. Further backward movement of the nozzle then withdraws the comb from constricting relation with respect to the nozzle opening thereby increasing the effective area of the nozzle opening to its normal value for continued normal cleaning operation during backward movement of the nozzle. Thus this desired movement of the comb element is automatically accomplished during normal operation simply by reversing the direction of movement of the nozzle and in a simple and efficient manner and does not add materially to the bulk or weight of the nozzle, nor otherwise detract from its normal desirable characteristics.

Referring now to the drawings and particularly to Sheet 1, in Fig. 1 is illustrated the general type of vacuum cleaner to which the present invention is primarily adapted although it will be understood it is likewise adaptable to the first type of vacuum cleaners previously described as well. As illustrated in Fig. 1 the particular vacuum cleaner combination shown includes a combined suction producing mechanism and dust container indicated generally at 30, a nozzle structure indicated generally at 32 secured to the end of a rigid wand or tube 34 and an interconnecting flexible tube 36.

While any suitable type of unit 30 may be employed in conjunction with the present invention, the particular unit shown by way of illustration is that disclosed and described in my United States Letters Patent No. 2,228,750, issued January 14, 1941, on Vacuum cleaner construction. The nozzle 32 itself comprises a transversely elongated main body portion 40 of hollow rectangular section and the bottom face thereof which is adapted to contact the floor is open for the purpose of receiving dust laden air in accordance with conventional practice. The lower marginal edges of the forward and rear faces of the main body portion 40 are provided, respectively, with forwardly and rearwardly extending flange portions 42 providing relatively broad shoe-like bases or shoes for supporting the nozzle on the floor. The top wall of the main body portion 40 inclines upwardly from the ends towards the center thereof at which point a hollow socket 44, extending at an angle to the vertical and horizontal is joined in the main body portion 40 and is adapted to receive the lower end of the wand 34 therein with a frictional fit. The main body portion 40 as shown is constructed from sheet metal, but may be of cast construction if desired.

At each lateral end of the main body portion 40 a rearwardly projecting flange or plate member 46 is rigidly fixed to the main body portion 40, these plates or flanges 46 being arranged with their planes extending vertically. Over the outside face of each of the flanges or plates 46 a plate member 48 is arranged and is of a size and shape substantially complementary to the size and shape of the corresponding end wall of

the main body portion 40 plus the flange or plate 46. The plates 48 are secured in place to the corresponding flanges 46 by means of screws 50 and nuts 52.

5 The end walls of the main body portion 40, as best indicated in Figs. 5, 6 and 7, are each provided with an upwardly extending slot 54 therein and through which slots project a shaft 56. The opposite ends of the shaft 56 are journaled in the plates 48 at opposite ends of the main body portion 40, and to the shaft 56 outwardly beyond each plate 48 a roller 58 is fixed thereto. It may be observed at this point that the shaft 56 is preferably positioned as closely as practical to the rear wall of the main body portion 40 and the rollers 58 are preferably of a diameter to project slightly downwardly beyond the plane of the lower face of the flanges or shoes 42 to better adapt them for frictional engagement with the carpet or other surface being cleaned. It will be appreciated that the rollers have such limited size that ordinarily they will imbed themselves in the nap of a carpet or rug so as to permit the shoes 42 to ride directly upon the upper surface of the carpet or rug during normal operation.

10 A comb element 60 is fixed to the shaft 56 within the main body portion 40 and extends for substantially the full distance between opposite ends of the main body portion. The comb element 60 includes a main body portion arranged radially with respect to the axis of the shaft 56 and an angularly offset end portion terminating in a serrated edge or comb 62 as best shown in Fig. 8.

15 The comb element 60 is thus fixed for rotation with the shaft 56 but is limited on its rotational movement by contact with the rear wall of the main body portion 40. Preferably rubber or other sound deadening strips 64 are secured as indicated in Figs. 5, 6 and 7 to the inner face of the rear wall of the main body portion 40 in a position to engage the comb element 60 at opposite limits of its rotational movement. The comb element 60 is made of such dimensions that when it is in its extreme limit of movement in a clockwise direction of rotation, as viewed in Figs. 5, 6 and 7, the comb 62 thereof projects slightly below the lower face of the shoes 42, the comb thus being positioned so as to imbed itself sufficiently in the nap of the carpet or rug being cleaned to insure its mechanically engaging and loosening any threads, lint or the like adhering to the surface of the carpet or rug. The radial dimension of the comb element 60 is also preferably such with respect to the position of the shaft 56 in the housing 40 that when the shaft 56 is rotated the comb 62 barely clears the inner surface of the forward wall of the main body 40 as illustrated in Fig. 6 for a purpose which will hereinafter be more fully explained. In this position the teeth of the comb are pointing upwardly which, of course, facilitates the removal of the threads or the like upwardly therefrom.

20 It will be appreciated that in the construction above described the shaft 56 with the comb element 60 thereon, the end plates 48 and the rollers 58 provide a unitary assemblage which may be applied to the main body portion 40 as a unit and may be secured in place by means of the screws 50 and nuts 52, and that the same unit may be correspondingly removed by removing the screws 50 and nuts 52 and simply lifting it out of the nozzle assembly. This feature makes for ease in manufacturing and service.

25 In the operation of the nozzle thus described

above it will be appreciated that an operator operates the nozzle in a conventional manner in cleaning a rug or carpet, that is the operator sets the associated vacuum producing mechanism in operation and simply runs the nozzle, with the open side facing downwardly, back and forth across the surface of the rug or carpet desired to be cleaned. With the construction thus described when the operator is grasping the wand 34 and pushing it forward causes the nozzle 32 to move forwardly over the surface of a rug or carpet, the initial movement of the nozzle in this direction, acting through the friction between the rollers 58 and the surface of the rug or carpet, will rotate the shaft 56 and consequently the comb element 60 in a clockwise direction of movement as viewed in Figs. 3, 5, 6 and 7 until the comb element 60 contacts the lower bumper 64 as illustrated in Fig. 5, and thereafter during further movement of the nozzle in a forwardly direction the wheels 58 will simply slide over the surface of the carpet. The comb element 60, however, during this forward movement is positioned with the comb 62 thereof in a position to engage the surface of the carpet or rug and to mechanically engage and loosen threads or lint which it comes into contact with on such surface.

When the forward stroke of the nozzle 32 is completed, then as soon as the ensuing back stroke is initiated the rollers 58 will be caused to rotate in a counterclockwise direction of rotation as viewed in Figs. 5, 6 and 7 with the result that a counterclockwise direction of movement will be imparted to the shaft 56 and comb element 60, this movement continuing until the comb 62 and comb element 60 contacts the upper bumper 64 which will thus prevent further rotation in this direction and thereafter the rollers 58 will slide on the surface of the carpet during the continued back stroke of the nozzle. The position of the comb element in such case is illustrated in Fig. 7.

It will be appreciated that the comb member 60 in passing from the position illustrated in Fig. 5 to the position illustrated in Fig. 7 will have to pass through the position illustrated in Fig. 6 in which the comb 62 is in close proximity to the forward wall of the main body portion 40, and in so moving will pick up the windrow of thread, lint or the like it has gathered during the forward movement and will mechanically transfer such windrow from the surface of the carpet up into the interior of the nozzle. When the comb element 60 is in the position illustrated in Fig. 6 it will be appreciated that the effective cross-sectional area of the air passage through the nozzle is materially reduced with the result that the air which is drawn over the forward edge of the comb member 60 and over the rear face of the shaft 56 is materially reduced with the result that the air which is drawn over the forward edge of the comb member 60 and over the rear face of the shaft 56 is materially increased in velocity at this time. This is important for the reason that in order to insure the thread and lint picked up by the comb 62 being removed therefrom and withdrawn further into the nozzle, a jet of high velocity air is extremely desirable if not necessary in order to insure complete cleaning of the comb. Thus with the construction described every time the direction of movement of the nozzle on the surface being cleaned is reversed the operative edge of the comb will mechanically pick up any material which it has gathered on the surface of the

carpet or the like and carry it up into the interior of the nozzle where it will be subjected to the effects of a high velocity stream of air which quickly, efficiently and assuredly removes all thread, lint and other material picked up by the comb.

It will be appreciated from the above explanation that the present invention provides a means whereby threads, lint and other material adhering more or less tenaciously to the surface of a carpet or rug may be effectively picked up through a vacuum cleaner nozzle without the necessity of mechanically driven means such as brushes and that the device of the present invention involves such relatively small and light parts that it does not materially increase the size of the nozzle nor the weight thereof and thus ideally adapts itself for use in connection with vacuum cleaner nozzles of the wand type, although being useful in any type of vacuum cleaner.

It will be understood that while the nozzle structure illustrated in Figs. 1 to 8, inclusive, is fully operative and capable of performing its intended duty, it lacks certain refinements which are considered desirable from a present day merchandising standpoint and such refinements are incorporated in the modification thereof illustrated in Figs. 9 to 11, inclusive. The construction shown in Figs. 9 to 11, inclusive, is somewhat similar to that shown in my United States Reissue Patent No. 21,256, issued November 7, 1939, except that the present nozzle does not embody the secondary high velocity nozzles of my earlier patent. In other words, the improved nozzle illustrated in Figs. 9 to 17, inclusive, includes a transversely elongated hollow main body portion indicated at 10, the bottom face of which is open to provide an air inlet passage 12. The main body portion 10 is shown of cast construction although it may, of course, be constructed from sheet metal if desired. The lower margins of the front and rear walls of the main body portion 10 are forwardly and rearwardly flanged, respectively, as at 14 to provide carpet engaging supporting surfaces and these are preferably rounded in a forward and rearward direction on their under faces, as indicated, to enable them to more readily slide over the surface of the carpet, rug or the like without interference.

Instead of providing a socket rigid with the main body portion of the nozzle for reception of the wand as in the first described construction, means are provided for hingedly securing the wand to the nozzle in the present construction. This is accomplished by providing centrally of the main body portion 10 an upstanding pocket portion 16 opening in a rearwardly direction. On each side of this pocket portion 16 but outwardly spaced from the margins thereof as indicated in Fig. 15 is a rearwardly directed flange or plate 18 formed integrally with the main body portion 10 and arranged with their inner faces in parallel relation with respect to each other and perpendicular to the plane of the bottom face of the nozzle. A hollow hinge member indicated generally at 20, open at its forward and rearward ends, is freely received between the plates 18 and is projectable into the pocket 16. The hinge member 20 is mounted for pivotal movement between the plates 18 by means of a bolt 22 rotatably received in the lower portion of the hinge member 20 in line with or immediately above the plane of the lower surface of

the nozzle and which bolt also projects through the plates 78, the bolt 82 being removably secured in place by means of a nut 84 threaded upon one end thereof. The plates 78 are joined together along the rearward portion of their lower margins by a cross-member 86 the forward and rearward edges of which are upwardly rounded and which is adapted to engage the surface of a rug or carpet being cleaned so as to provide a stabilizing shoe or surface for the nozzle structure.

The hinge member 80 is formed to provide an upwardly and rearwardly extending socket 88 for reception of a conventional wand, such as the wand 34 illustrated in Fig. 1, and its upper surface forwardly of the lower end of the socket 88 is cylindrically curved as at 90 about the center of the bolt 82 as a radius. The sides of the hinge member 80 are flat and parallel with each other and with the inner faces of the plate 78. As best illustrated in Fig. 12, the rear marginal edge of the upper wall of the pocket 76 is horizontally grooved and receives therein the upper forwardly projecting flange of a Z-sectioned sealing element 92. The lower and rearwardly directed flange of the sealing element 92 bears against the curved upper surface 90 of the hinge member 80 thereby to seal the joint between the surface 90 and the upper wall of the pocket 76 against leakage of air therethrough. Preferably the sealing element 92 is initially formed so that the lower flange thereof is deflected downwardly and is constructed from resilient material such as rubber composition so that upon assembly the free edge of the lower flange will resiliently press against the surface 90 to enhance the sealing effect thereof. Additionally, it will be appreciated that when the nozzle is being operated and connected to a suitable source of suction the reduced pressure on the interior of the nozzle cooperating with the atmospheric pressure on the exterior thereof will tend to press the lower flange of the sealing element 92 more securely against the surface 90 thereby to enhance the sealing effect thereof.

As best brought out in Fig. 15 the main body portion 70 along the vertically directed rear edges of the pockets 76 and immediately inwardly of the corresponding plate 78 is provided with a vertically directed rearwardly opening groove in which a sealing element 94, which may be of the same material and of identically the same section as sealing element 92, is received, the rearward flanges thereof engaging the sides of the hinge element 80 thereby to seal the joint between the sides of the hinge element 80 and the sides of the pocket 76 against the flow of air therethrough.

That portion of the hinge member 80 surrounding the bolt 82 is formed to a partially cylindrical shape on its under-surface and of such dimensions that it projects downwardly to substantially the plane of the lower faces of the flanges 74 and shoe 86 thereby to seal the space between the lower surface of the hinge 80 and the surface of the rug or carpet being cleaned against an undesirable leakage of air therethrough. It will be appreciated, however, that unless otherwise provided for with the construction thus far described, with the lower face of the nozzle flat on the surface of a carpet or rug as will normally occur in operation, all of the air drawn into the nozzle must be drawn through the nap of the carpet or rug in finding its way into the nozzle, this being desirable under ordinary circum-

stances. However, occasions do arise where it is desirable to provide one or more streams of air of relatively high velocity flowing into the nozzle in order to facilitate the picking up of some piece of material, objects or the like from the surface being cleaned and which could not otherwise be accomplished by the stream of low velocity air required to first pass through the nap of the carpet or rug and then into the nozzle.

In accordance with one phase of the present invention in order to obtain a plurality of relatively small streams of high velocity air under such conditions the partially cylindrical surface of the nozzle member 80 underlying the bolt 82 is provided with a plurality of forwardly and rearwardly directed grooves 96 therein as best brought out in Figs. 12 and 17. These grooves 96, as best illustrated in Fig. 12, are disposed at an angle to both the horizontal and vertical when the hinge member 80 is in its normal position of operation as illustrated in Fig. 12. If the wand is raised by the operator so as to cause the hinge member 80 to pivot in a counterclockwise direction of rotation as viewed in Fig. 12 so as to bring the bottom of the slots 96 into parallelism with the surface of the rug or carpet being cleaned, the slots 96 provide open and unobstructed passages leading from the outside air directly into the interior of the nozzle through which a plurality of relatively small streams of air may flow at high velocity, and if some particular object which it is desired to pick up from the surface of the rug or carpet being cleaned and which requires such high velocity air to enable it to be picked up from the surface being cleaned, is maneuvered into the central portion of the opening 72 in the nozzle it will be subjected to these streams of high velocity of air and be withdrawn through the nozzle into the suction producing means.

When the nozzle member 80 is returned to its normal position of operation illustrated in Fig. 12, it will be appreciated that the effect of cross-sectional area of the grooves 96 open to the flow of air from the outside into the nozzle is materially reduced and it will also be appreciated that if the nozzle member 80 is pivoted in a clockwise direction of movement from the normal position illustrated in Fig. 12, the ungrooved portion of the nozzle member 80 may be brought into contact with the surface being cleaned thereby completely shutting off the grooves 96 from the direct flow of air therethrough. This construction, therefore, provides a means whereby a plurality of relatively small streams of air at high velocity may be optionally obtained during operation of the nozzle, together with the attendant advantages and without the necessity of adding any additional parts or masses of metal to the construction.

In adapting the previously described comb structure to the nozzle construction illustrated in Figs. 9 to 17, inclusive, the interior rear wall of the main body portion 70 is preferably provided with a strip of sound deadening material 100, best illustrated in Figs. 12 and 15, and which may be of rubber or other suitable material, for engagement with the comb member and for limiting the rotatable or oscillatable motions of the same in opposite directions. In the present case the comb structure includes a shaft 102 carrying a sheet metal comb member 104 as best illustrated in Fig. 12. The upper edge of the comb member 104, as illustrated in Fig. 12, is formed into an eye for reception of a shaft 102 to which it is

rigidly secured and the lower marginal edge portion thereof is bent forwardly and downwardly as indicated and terminates in a serrated comb edge 106 as in the construction previously described. In this case, however, the shaft 102 is so located that the surrounding portion of the comb member 104 substantially contacts the bumper strip 100 at all times and, therefore, prevents the flow of any material amount of air upwardly between the comb member 104 and the rear wall of the main body portion 70. It might be noted that the bumper strip 100 is cut down in height over the width of the pocket 76 and the rear wall of the main body portion 70 is extended over the width of the pocket 76 for the height of this portion of the bumper strip 100 in order to provide support for the bumper strip 100 thereacross, such rear wall being otherwise cut away over the cross-sectional area of the pocket 76.

The opposite ends of the main body portion as best brought out in Figs. 9 and 14, are formed to provide pockets 108 separated from the remainder of the interior of the main body portion 70 by transverse walls 110. These transverse walls are upwardly slotted as at 112, best seen in Figs. 12 and 14, for passage of the opposite ends of the shaft 102, the effect being the same as the slots 54 in the end walls of the main body portion of the nozzle first described. Within each pocket 108 and in closely adjacent relationship with respect to the corresponding wall 110 a roller 114 is fixed to the corresponding end of the shaft 102 in any suitable way such as by a set screw 115 (Fig. 16). The rollers 114 project downwardly below the plane of the lower face of the nozzle a distance corresponding to that in the construction first described. Outwardly beyond each roller 114 a bearing 116 rotatably receives the corresponding end of the shaft 102 therein. The exterior surface of the bearing 116 is partially spherical in conformation and is received within the lower frusto-conically shaped end portion of a downwardly extending post or bracket 118 formed integrally with the upper wall of each of the pockets 108 as best shown in Fig. 13. A boss 120 formed integrally with the main body portion 70 in one corner of each of the pockets 108, acting through a cooperating screw 122, serves as a support for a sheet metal clamping member 124 having a partially spherical outer end portion which receives the lower face of the corresponding bearing 116 therein and forces the bearing upwardly into position against the lower end of the corresponding post 118. It will be appreciated that by this means the bearings 116 are rendered self-aligning and at the same time by simply removing the screws 112 the bearings 116, the shaft 102 and the comb member 104 may be readily and quickly removed for servicing or the like and for the same reason may be quickly and accurately positioned in manufacture and service.

As in the construction first described it will be appreciated that the width of the opening 72 is originally designed so that the slight width of the comb member 104 and its shaft 102 does not unnecessarily restrict the desired normal working area of the nozzle and that when the comb member 104 is in either extreme limit of its movable positions the effective open area of the nozzles is at its maximum value. It will also be appreciated that when the comb member 104 is moving from one limit of its movable position to the other during initiation of the reversal of movement of the nozzle in a forwardly or rearwardly direction during normal operation, the

comb edge 106 of the comb member will pass into relatively close proximity to the forward wall of the main body portion 70 to momentarily restrict the effective area of the nozzle and create a high velocity stream of air past its edge 106 to more efficiently remove any threads, lint or other material which may have been picked up thereby in the same general manner as in the nozzle construction first described.

There are certain types of carpets or rugs in which the nap forming threads are looped and which, therefore, do not lend themselves to the use of a comb structure of the general type described. In case the nozzle is to be used on such a carpet means are preferably provided for locking the comb member 104 at its upper limit of movement. While any suitable means may be provided for this purpose, one simple and effective means is shown in the drawings and comprises a screw 130, threaded through the wall of one of the pockets 108, the lefthand pocket as illustrated in Figs. 9 and 10, and positioned so that it may be threaded inwardly to bring its inner end into binding relation with respect to the corresponding roller 114 in the manner illustrated in Fig. 16. The screw 130 has a large knurled head enabling it to be readily manipulated by the fingers of the user. Thus where it is desired to lock the comb member 104 in inoperative position, the nozzle is simply drawn in a rearwardly direction on a surface a distance sufficient to insure the comb being moved to the upper extremity of its movable position, and then the screw 130 is simply threaded inwardly until it is arranged in binding relationship with respect to the corresponding roller 114, whereupon the nozzle may then be operated in the normal manner with the effects of the comb member eliminated.

It is common practice in connection with vacuum cleaner nozzles of the type described to encircle them with a band of soft non-metallic material serving as a bumper so that in event the nozzle strikes a piece of furniture the furniture will not be marred. Means are provided in accordance with the present phase of the present invention to obtain this result in connection with the present nozzle and additionally such means are so constructed and arranged as to simplify and reduce the cost of manufacture of the nozzle as well as to blend in with the nozzle and streamline the shape thereof. This member is preferably formed from rubber or rubber composition and is shaped to be received by the upper faces of the flanges 74 and to bear against the vertical faces of the main body portion 70 around its full extent except between the plates 78.

In connection with this feature of the present invention it will be noted that the upper wall of the main body portion 70, in order to better adapt it to the desired contour of the finished nozzle, is provided with a convex outer surface of greater height at the front wall thereof than at the rear wall thereof. Along the forward face of the main body portion 70 this bumper, which is indicated generally at 140, is formed to provide a relatively thick horizontally directed bottom wall 142 the bottom face of which lies directly in contact with the upper face of the forward flange 74, and this is integrally joined at its forward end to an upwardly and rearwardly curving wall portion 144 which terminates against the forward face of the main body portion 70 and with its outer surface in flush relationship to the upper wall of the main body portion 70 at the forward edge thereof. The inner edge

of the portion 42 contacts the forward face of the main body portion 70 so that a hollow chamber 146 is formed interiorly between the parts 142 and 144 and the forward face of the main body portion 70, this serving to provide an unusually resilient bumper.

At its opposite ends the bumper 140 is provided with solid end wall portions 146, as best shown in Fig. 9, integrally joined to the forward portion of the bumper and extending rearwardly around the end portion of the main body portion 70 where each end portion 146 joins with a correspondingly inwardly directed portion extending to the corresponding sides of the pocket 76. As best illustrated in Figs. 13 and 16 these last mentioned portions each include a horizontally directed portion 148 joined at its rear edge to an upwardly and forwardly curving portion 150 the upper edge of which bears against the rear wall of the main body portion 70 and its upper surface is arranged in flush relationship with the upper face of the main body portion 70 at the rear edge thereof as indicated. Thus the rear portion of the bumper 140 also cooperates with the rear face of the main body portion 70 to provide a hollow structure and the whole bumper cooperates with the main body portion to impart a pleasing streamlined effect thereto as well as an effective bumper of minimum weight. This construction is primarily important from a commercial standpoint inasmuch as it allows the main body portion of the nozzle to be constructed in a simple manner most efficient for casting and machining purposes and in a shape that in and of itself would be unacceptable from a commercial standpoint. Additionally, it forms a shield for the major area of the otherwise exposed metal surfaces of the nozzle structure which, therefore, eliminates the requirement of plating and/or polishing of these surfaces by shrouding the same and, therefore, serves to further make the nozzle construction as a whole more economical to produce.

It will be appreciated that the bumper projects outwardly beyond the outer edges of the flanges 74 and beyond the end surfaces of the main body portion 70 so that in running the nozzle over the floor it is substantially impossible to bring any metallic portion thereof into contact with a piece of furniture, and the construction of the bumper in forming the hollow chambers having the resilient walls renders the construction exceptionally flexible and obviates any danger of any possible marring or scratching of any object with which the bumper may contact. The bumper may be secured in place on the main body portion 70 by any suitable means such as adhesive, screws, or the like.

In Figs. 18, 19 and 20 a construction is shown that is identical to the construction shown in Figs. 9 to 17, inclusive, in every respect except for the construction of the rollers and the method of securing them to the comb shaft. Consequently all parts illustrated in Figs. 18, 19 and 20 bear the same numerals as in Figs. 9 to 17, inclusive, with the exception of the rollers themselves and, accordingly, it is only necessary to describe the difference in the construction of the rollers in Figs. 18, 19 and 20 in order to render the entire construction understandable.

In the construction illustrated in Figs. 18, 19 and 20 means are provided for clutching each wheel to the comb shaft so that the wheels may rotate freely of the shaft in one direction and will be locked in driving relation to the shaft

when rotating in the opposite direction, the wheels being arranged so that one will drive the shaft when rotating in one direction and the other will drive the shaft when rotating in the opposite direction. While any suitable type of ratchet or free wheeling clutch may be employed for this purpose, in the particular construction shown by way of illustration each roller includes a central cylindrical portion 160 suitably fixed to the shaft 102 as by means of a key 162, and an enveloping annular rim portion 164 rotatably mounted upon the portion 160. Radially extending webs 166 and 168 at the opposite ends of the portions 160 and 164, respectively, extend in axially overlapping relationship with respect to the corresponding ends of the other members as best illustrated in Fig. 18. The peripheries of the portions 160 are notched out as at 170, each notched portion having a substantially radial end wall portion and a bottom portion perpendicular thereto so that the notches are more or less wedge shaped when viewed axially of the rollers. It is to be noted from an inspection of Figs 19 and 20 that the notches in the member 160 at one end of the nozzle extend angularly in the opposite direction from the notches in the member 160 at the opposite end of the nozzle with respect to the axis of the shaft 102. A roller 172 is received in each of the notches 170 in parallel relation to the axis of the shaft 102 and light coil spring 174 cooperates between each roller 172 and the radially disposed wall of the corresponding notch 170 to urge the roller 172 outwardly away from said wall and into binding relationship with respect to the inner wall of the notch and the inner wall of the annular rim member 164. The construction thus provided is a conventional form of one-way clutch permitting rotation of the corresponding rim member in one direction but preventing relative rotation in the opposite direction with respect to its central member 160. With this construction and keeping in mind that the clutches of the rollers at the opposite end of the nozzle operate in the opposite direction, it will be appreciated that during forward movement of the nozzle the rim 164 of the righthand roller, as viewed in Fig. 18, will be locked to the central portion 160 thereof and consequently to the shaft 102 during forward movement of the nozzle, the rim portion 164 of the lefthand roller rotating freely upon its central portion 160 at such time. However, when the direction of movement of the nozzle is reversed, that is, the nozzle is moved in a rearwardly direction, the rim of the righthand roller as viewed in Fig. 18 will be released from driving relation with respect to its corresponding central portion 160 and the rim 164 of the left-hand roller will be drivingly engaged with its central portion 160 and, consequently, during rearward movement, the lefthand roller only will serve to operate the shaft 102 and the comb member 104. One of the advantages of such a construction is that it is only necessary to slide one roller at a time over the floor during the major portion of the forward and rearward movements of the nozzle thereon.

Having thus described my invention, what I claim is:

1. In combination, a hollow vacuum cleaner nozzle having an open side adapted for contact with a floor, a comb element positioned within said nozzle and mounted therein for rotatable movement about a line adjacent the rear wall thereof, said comb element when in normal operative position for forward movement including a forwardly projecting portion terminating in a

serrated free edge disposed in said opening in a position to engage the surface of a floor, movable floor engaging means carried by said nozzle and adapted for frictional engagement with the surface of a floor, means interconnecting said floor engaging means and said comb element for inter-related movements, said comb element being of such radial dimension that the serrated edge thereof passes into close proximity to the forward wall of said nozzle during movement of said element between its opposite limits of movement, whereby to momentarily decrease the effective cross-sectional area of said nozzle to the serrated edge of said comb element and increase the velocity of air flow over said edge, means limiting rotation of said comb element in one direction to a position in which said serrated edge thereof is disposed below but in close proximity to the plane of said open side, and means limiting rotation of said comb element in the opposite direction to a position in which said serrated edge is disposed a material distance above said plane of said open side.

2. In combination, a hollow vacuum cleaner nozzle having an open side adapted for contact with a floor, a comb element positioned within said nozzle and mounted therein for rotatable movement about a line adjacent the rear wall thereof, said comb element when in normal operative position for forward movement including a forwardly projecting portion terminating in a serrated free edge disposed in said opening in a position to engage the surface of a floor, and a roller at the opposite sides of said nozzle member arranged for engagement with a floor, means forming a driving engagement between one of said rollers and said comb element for effecting simultaneous operation of said comb element only when said nozzle member is being moved in a forwardly direction, means forming a driving connection between the other of said rollers and said comb element effective only when said nozzle member is being moved in a rearwardly direction, means limiting rotation of said comb element in one direction to a position in which said serrated edge thereof is disposed below but in close proximity to the plane of said open side, and means limiting rotation of said comb element in the opposite direction to a position in which said serrated edge is disposed a material distance above said plane of said open side.

3. In combination, a hollow vacuum cleaner nozzle having an open face adapted for engagement with a floor, a shaft in said nozzle member extending from one side thereof to the opposite side thereof, a comb member fixed to said shaft and rotatable therewith, a roller mounted on each end of said shaft in position to engage a floor, one-way clutch operative to drivingly connect one of said rollers to said shaft only when said nozzle member is moving in a forwardly direction, a one-way clutch operative to drivingly connect the other of said rollers to said shaft and operative only when said nozzle member is moving in a rearwardly direction, means limiting rotation of said comb member in one direction to a position in which the free edge thereof is disposed below but in close proximity to the plane of said open face, and means limiting rotation of said comb member in the opposite direction to a position in which the free edge thereof is disposed a material distance above said plane of said open face.

4. In combination, a hollow vacuum cleaner nozzle having an open face adapted for engagement with a floor, a comb element in said nozzle

having cylindrical journal portions projecting from opposite ends thereof, a bearing having a partially spherical exterior surface received on each of said journal portions, posts fixed with respect to said nozzle having sockets for reception of said bearings, means for releasably holding said bearings in said sockets, floor engaging means movably associated with said nozzle operatively engaging said comb element for inter-related movement therewith, means limiting rotation of said comb member in one direction to a position in which the free edge thereof is disposed below but in close proximity to the plane of said open face, and means limiting rotation of said comb member in the opposite direction to a position in which the free edge thereof is disposed a material distance above said plane of said open face.

5. In combination, a hollow vacuum cleaner nozzle having an open side adapted for engagement with a floor, a comb member mounted within said nozzle for rotational movement about a line proximate to and parallel with one longitudinal extending edge thereof and proximate to the rear wall of said nozzle, the remaining longitudinally extending edge of said comb member being serrated and being located approximately in the plane of the open-face said nozzle at one limit of its movable positions and being positioned in elevated and approximate relation to the rear wall of said nozzle when at the opposite limit of its movable positions, said comb member being substantially imperforate except for said serrated edge and said serrated edge sweeping into close relationship to the front wall of said nozzle when moving from one of said limits to the other of said limits whereby to largely restrict the flow of air through said nozzle past said comb to the serrated edge of said comb at such time, and means operatively associated with said comb member adapted for frictional engagement with a floor operative to move said comb member between the opposite limits of its movable positions upon reversal of direction of movement of said nozzle on a floor.

6. In combination, a hollow vacuum cleaner nozzle having an open side adapted for engagement with a floor, an angularly sectioned comb member mounted within said nozzle for rotational movement about a line proximate to and parallel with one longitudinally extending edge thereof and proximate to the rear wall of said nozzle, the remaining longitudinally extending edge of said comb member being serrated and being directed toward the forward edge of said opening approximately in the plane of the open-face said nozzle when at one limit of its movable positions and being positioned in elevated and proximate relation to the rear wall of said nozzle when at the opposite limit of its movable positions, said comb member being substantially imperforate except for said serrated edge and said serrated edge sweeping into close relationship with respect to the front wall of said nozzle when moving from one of said limits to the other of said limits whereby to largely restrict the flow of air through said nozzle past said comb to the serrated edge of said comb at such time, and a wheel operatively associated with each end of said comb member and adapted for frictional engagement with the floor for moving said comb member between opposite limits of its movable positions upon reversal of direction of movement of said nozzle on a floor.
